UNITED STATES PATENT OFFICE.

JOSEPH WILLIAM GUIMONT, OF LACHINE, QUEBEC, CANADA, ASSIGNOR TO LUDGER LEMIEUX, OF MONTREAL, CANADA.

RADIATOR.

Application filed November 18, 1927. Serial No. 234,267.

The present invention relates to improvements in radiator construction and has particular reference to the structure of the individual radiator sections, constituting an improvement over my co-pending application, granted to me under Letters Patent No. 1,670,618 bearing date of May 22nd, 1928.

An important object of the invention is the provision of a radiator formed to provide a relatively large exposed heating area.

A further object of the invention is the provision of a radiator designed to provide an interior air passage adapted to increase the circulation of the heated air through the radiator.

Still another object of the invention is the provision of a radiator which is comparatively simple, durable and compact in construction.

Other objects and advantages of the invention will become apparent as the description progresses.

In the accompanying drawing forming a part of this specification and in which like reference characters are employed to designate corresponding parts throughout the same:

Figure 1 is a side elevational view of one of the radiator sections.

Figure 2 is an inside elevation of one of the complementary divisions of the sections,

Figure 3 is a vertical transverse section taken on the line 3—3 of Figure 1,

Figure 4 is an enlarged transverse section taken on the line 4—4 of Figure 1, and

Figure 5 is a similar section taken on the line 5—5 of Figure 1.

Referring to the drawing, wherein for the purpose of illustration is shown a preferred embodiment of the invention, the numeral 10 generally designates an assembled section of a radiator constructed in accordance with my invention.

Each section embodies a pair of complementary, longitudinally divided semi-sections 11 detachably secured at the upper and lower ends to form the complete radiator section. Each of the semi-sections is of rectangular elongated form, provided with a longitudinal central recess 12 dividing the intermediate portion of the semi-section into longitudinal complementary side legs 13 connected at the upper and lower extrem-

ities. Each of the semi-sections are of hollow tubular form providing a rectangular shaped continuous conduit. The interior contacting wall of each semi-section is provided with parallel longitudinally directed grooves or inwardly projecting corrugations 14 extending the entire length of the semi-section, as clearly indicated in Figure 2. At the upper and lower ends, the semi-sections are provided with screw threaded openings 15 formed in the interior side and adapted to be arranged in registering positions. The upper and lower ends of the exterior sides are also formed with screw threaded openings 16 for assembly of the sections to form a communicating radiator unit. As shown to advantage in Figure 4, the inner medial portion of the inner wall of each semi-section between the grooves 14, is offset outwardly with respect to the plane of the marginal portions so that the inner portions will contact in assembly while the marginal surfaces will be maintained in separated positions.

The semi-sections are connected to form a complete radiator section by means of an exteriorly threaded tubular nut 17 which is threaded through the adjacent registering openings 15 to secure the central portions of the inner walls together. In this connection, it will be noted that the openings 15 are preferably in transverse alignment with the larger exterior openings 16 for convenient introduction of the nut 17.

Thus, in assembly, the component sections of the radiator will embody a pair of complementary, rigidly connected semi-sections designed to provide a continuous rectangular shaped conduit in the longitudinal side portions of which are formed substantially oval shaped ducts having lateral communication with the atmosphere through the longitudinal recess formed between the marginal portions of the semi-sections. This construction will permit exceedingly efficient circulation of the air through the radiator so as to obtain the utmost efficiency from the circulating fluid which may comprise hot water, steam or the like.

It is to be understood that the form of my invention herein shown and described is to be taken as a preferred example of the same, and that various changes as to the shape, size, and arrangement of parts may be re-

sorted to without departing from the spirit of the invention or the scope of the subjoined claims.

Having thus described my invention, I

5 claim:—

1. A radiator section comprising a pair of complementary hollow semi-sections formed with inwardly projecting corrugations at their interior faces, and means for 10 detachably connecting the semi-sections so that the respective corrugations will be positioned in opposed registration and the outer longitudinal portions of the inner faces arranged in spaced position to form a lateral 15 recess communicating with the corrugations.
2. A radiator section comprising a pair of complementary longitudinally divided semi-sections, each semi-section including a rectangular shaped conduit having longitudinally directed inwardly projecting corrugations formed in the interior wall at the 20 sides thereof, means for detachably connecting the semi-sections so that the corrugations will be arranged in opposed positions 25 to form a circulating duct communicating with the atmosphere through a recess

formed between the marginal interior sides of the semi-sections, and means for connecting the assembled sections to form a radiator unit.

3. A radiator section comprising a pair of longitudinally divided semi-sections formed to provide a rectangular shaped conduit, the inner wall of each semi-section being formed with inwardly depressed corrugations in the longitudinal sides thereof, the intermediate portion of said inner wall being formed to project outwardly beyond the plane of the exterior marginal portions to provide a longitudinal recess between the 40 said marginal portions in assembly, means for detachably connecting the semi-sections to form an assembled radiator section, said means being formed to permit communication between the said semi-sections, and means whereby the assembled sections can be communicatingly connected to form a 45 radiator unit.

In witness whereof I have hereunto set my hand.

JOSEPH WILLIAM GUIMONT.
